UNITED STATES PATENT OFFICE.

JAMES T. HOGAN, OF JERSEY CITY, NEW JERSEY, ASSIGNOR TO THE SINGER MANUFACTURING COMPANY, OF ELIZABETH, NEW JERSEY, A CORPORATION OF NEW JERSEY.

BUTTONHOLE-SEWING MACHINE.

1,085,910.

Specification of Letters Patent.

Patented Feb. 3, 1914.

Application filed May 4, 1911. Serial No. 625,058.

To all whom it may concern:

Be it known that I, JAMES T. HOGAN, a citizen of the United States of America, and a resident of Jersey City, county of Hudson, 5 and State of New Jersey, have invented certain new and useful Improvements in Buttonhole-Sewing Machines, of which the following is a specification, reference being had to the accompanying drawings, forming a 10 part thereof.

My invention relates to buttonhole sewing machines of the type designed for producing buttonholes with side stitches upon either side thereof, and barring stitches of 15 greater amplitude at the ends of the buttonhole, such barring stitches being substantially parallel with the side stitches.

I have found by experience that where the barring stitches are formed while there is a 20 relative longitudinal feed between the work and the stitch forming mechanism, a slight gap in the stitching is apt to result at the point where the side stitches connect with the barring stitches. This is not only un- 25 sightly, but leaves a weak place in the buttonhole.

The present object of my invention is to avoid such a gap, and to this end I so design and construct the machine as to cause 30 the longitudinal feed of the work clamp, by which the work being operated upon is supported, to be suspended for a brief space of time, at just the point at which the barring and side stitches merge into each other. By 35 thus suspending the feed I crowd the stitches slightly at these points and so obviate any possible chance of there being a gap.

In the particular embodiment of my invention shown herein the work clamp feed is 40 produced by a substantially heart-shaped cam, and to procure the desired result I provide short concentric portions or dwells in the cam at the proper points therein, thereby modifying the shape thereof from the 45 true heart-shape to a special form wherein the feed instead of being continuous will be suspended temporarily at the proper intervals for the desired purpose.

In order that my invention may be fully 50 understood, I will now proceed to describe an embodiment thereof, having reference to the accompanying drawings illustrating the same, and will then point out the novel features in claims.

55 In the drawings: Figure 1 is a view in

partial side elevation and partial longitudinal vertical section of a machine in which my invention is employed. Fig. 2 is an underside view of the same. Fig. 3 is a detail transverse sectional view therethrough upon the line 3—3 of Fig. 2. Fig. 4 is a detail top view of certain parts thereof with the upper arm and parts carried thereby removed. Fig. 5 is a detail view in horizontal section taken immediately beneath the bed 65 plate, showing the work clamp operating cams employed, together with the parts in direct connection with the said cams. Fig. 6 is an enlarged view of the said cams. Fig. 7 is a diagrammatic view showing the development of the said cams. Fig. 8 is a diagrammatic view of the stitching of a buttonhole made upon the machine herein illustrated.

The machine, in general, comprises the 75 usual bed plate 10 and overhanging arm 11. Mounted in the upper arm is the usual main driving shaft 12 which operates to reciprocate the needle bar 13, and through a cam 14 and certain correlated parts produces lateral or jogging movements of the needle bar 80 necessary for the production of the stitches.

Supported upon the bed plate of the machine is the carrying plate 15 for the work clamp 16. This carrying plate 15 is mounted 85 upon a supporting plate 17, with respect to which it may have a limited longitudinal movement, suitable guides 18 being provided for defining such movement. The supporting plate 17 is similarly guided transversely 90 in the machine by guides 19 whereby it, together with the parts supported thereby, may have a limited transverse movement in the machine.

Mounted immediately beneath the bed 95 plate and upon a stud 20 as an axle, are cams 21—22 for imparting feed movements and lateral shifting movements respectively to the work clamp, and a ratchet wheel 23 through which movements of rotation are 100 imparted to the cams. The cam 21 engages a stud 24 carried by one arm 25 of a bell crank lever which is pivoted at 26 to the bed plate of the machine, the other arm 27 being connected by means of a stud 28 with the 105 clamp plate 15. As the cam groove 21 approaches nearer to, or departs farther from its axis of rotation, it swings the bell crank lever 25—27 about its axis 26, and so imparts a longitudinal feeding movement in 110

one direction or the other, *i. e.*, either forward or backward, to the work clamp carrying plate 15, and hence to the work clamp. The shifting movements necessary to transfer the work between the positions to receive side stitches along one side thereof and upon the other, and an intermediate position to receive barring stitches, is effected by means of the cam 22, which cam engages a 5 stud 29 carried by the arm 30 of a bell crank lever which is pivoted about a stationary axle 31 also secured to the bed plate of the machine, the other arm 32 of the said bell crank being connected by means of a stud 33 10 with the supporting plate 17. The movements of the bell crank lever 30—32 about its axis caused by the cam 22, will move the supporting plate 17 transversely in the machine between the guides 19—19 so as to 15 produce the proper lateral shifting movements for the purpose above described, as will be well understood.

The step by step movements of rotation which as has been stated, are transmitted to 20 the cams 21—22 through the ratchet wheel 23, are imparted to the ratchet wheel by means of the usual pawl 34 and pawl carrying plate 35 to which oscillating movements are imparted by means of a cam or eccentric 36 25 upon the vertical shaft 37, the said cam or eccentric engaging a rocking lever 38, one end of which is connected through a link 39 with the plate 35. The vertical shaft 37 is driven by the main shaft as is usual. Se- 30 cured to the feed wheel 23 is still another cam 40 whose function is at the required moment to so operate upon the stitch forming mechanism as to increase the amplitude of the jogging or lateral movements of the 35 needle bar at the proper moment for the production of barring stitches. This cam operates through a lever 41 and a link 42 upon a pivoted plate 43 whose angular position defines the length of movement of the 40 jogging stitches imparted, the construction and position of the cam 40 being so designed with respect to the construction and position of the cams 21 and 22 that the barring 45 stitches will be produced at the time the work is being presented by the work clamp 50 to the needle, at the opposite ends of the buttonhole.

Further detail description or illustration of the various parts, than has been given, is 55 unnecessary herein, because of the fact that the machine as so far described and shown, except for the peculiar shape of the cam 21, forms no part of my present invention, the illustration and description so far as it has 60 gone having been merely given for the better understanding of that portion of the machine which does contain my invention.

The relative positions of the work clamp necessary for the production of the button- 65 hole, will be better understood by reference

to Fig. 8. In this figure 44 represents the side stitches upon one side of the buttonhole, 45 the side stitches upon the other side of the buttonhole, 46 the barring stitches at one end of the buttonhole, and 47 the barring stitches at the other end of the buttonhole. The feed wheel 23, together with the cams carried thereby, makes one complete revolution for each buttonhole produced, and when the high portion 48 of the cam 22 is 70 reached the work clamp is moved to the right as shown in the drawings, to so position it with respect to the stitching mechanism that the stitches 44 on the left of the buttonhole will be formed. The change 75 to the lower portion 49 of the cam shifts the work clamp to the left as viewed in the drawings, whereby the work clamp will be positioned with respect to the stitching mechanism to receive the side stitches 45, 80 while the movement to the intermediate portions 50—50 of the cam 22 will bring the work clamp to an intermediate position 85 wherein the barring stitches will be formed. The feed cam 21 has a portion 51 which 90 rises continuously from the point therein nearest to the axis of rotation of the cam, to the point therein farthest away from such axis of rotation, and it has another portion 52 which drops from the highest to 95 the lowest point, but not, however, continuously. This latter part 52 is interrupted at two points 53—54, at each of which points there is a dwell, that is to say, the cam at each of the two points 53 and 54 is concentric for a short space. I refer to Fig. 7 for a diagrammatic lay-out of the said cam upon an enlarged scale. This cam may be read in connection with the diagrammatic view Fig. 8, 100 with the following understanding of Fig. 8. The work commences in Fig. 8 at the point I, and continues uninterruptedly throughout the whole length of the buttonhole, to the point II, thereby producing the side stitches 44 for the entire length of one side 105 of the buttonhole. Thereafter the end barring stitches 46 are formed ending at the point III. Between the point III and the point VI, the side stitches 45 are formed, and thereafter the end barring stitches 47 are formed whereby the buttonhole is completed. The portion of the cam diagram in 110 Fig. 7 between the radial line I and the radial line II, (being the portion designated by the reference character 51 in Fig. 6,) represents the movement of the work in the production of the side stitches 44 shown in Fig. 8, wherein the work moves from the point I to the point II. The barring stitches 46 are formed upon the first portion of the return movement of the work, and the portion of the cam corresponding thereto is 115 that part contained between the radial lines II and III. At the moment the work reaches the point III wherein the change is 120

125 130

135

made from barring to side stitches, there is a dwell portion of the feed cam represented between the radial lines III and IV in Fig. 7, the corresponding positions in the button-hole diagram Fig. 8 also being designated by the reference characters III and IV. This suspends the feeding movement of the work at the commencement of the formation of the side stitches, thereby crowding the 5 side stitches at the termination of the barring stitches and preventing any undesirable gap being formed. The work clamp from this point is now fed continuously until just before the barring stitches 47, at 10 the opposite end of the buttonhole, are reached, this portion of the feed being represented between the radial lines IV and V in the diagrammatic view Fig. 7. Thereafter the feed is again suspended for a dwell defined by the movement of the cam between 15 the radial lines V and VI, whereby side stitches are crowded just at the point at which they merge in with the end barring stitches, and thereafter the end barring 20 stitches are formed during a progressive feeding movement of the work clamp represented as between the radial lines VI and VII in the diagrammatic view Fig. 7. In the cam shown there is a slight dwell between the point VII and the point I, but this merely represents a slight dwell between the completion of one buttonhole and 25 the commencement of another.

By providing the feed cam with the two 30 dwells at the proper points whereby the longitudinal feeding movements of the work is suspended at the time the transition is made from side to end stitches, or end to side stitches, any possible gap at this point 35 is avoided, the buttonhole is strengthened, and unsightliness in this connection is avoided. It will also be seen that by constructing the feed cam in the manner hereinbefore set forth I provide an exceedingly 40 simple mechanism for accomplishing the result, no extra cam or cams or other parts being necessary to produce the result, the only change from the ordinary machine being a slight change in the shape of the 45 cam 21.

As will be evident from the foregoing description, the independent actuation of the needle-jogging cam 14 and the feed-cam 21 produces an uncertainty in the relative 50 timing of changes in the amplitude of the needle-jogging movements and those of the feeding movements for the side-stitching and barring operations, and this uncertainty is increased by provision of adjusting means 55 for varying the speed of rotation of the

feed-cam for different conditions of button-hole stitching. By the present improvement, the gap which is liable to occur under such circumstances between the barring stitches and the adjacent stitches formed in the second side-stitching operation is obviated by the application of one or more filling stitches at the points where such gaps would otherwise occur. 65

What I claim is:

1. In a buttonhole sewing machine, the combination with stitch-forming mechanism including a reciprocating needle, a work-clamp, means for producing relative jogging movements between the needle and work-clamp, and means for periodically varying the amplitude of said jogging movements to change the length of the consecutive stitches, of means for imparting longitudinal feeding movements to the work-clamp and for temporarily suspending such feeding movements intermediate the extreme positions of the work-clamp and immediately prior to the change in amplitude of said jogging movements. 70

2. In a buttonhole stitching machine, the combination with stitch-forming mechanism including a reciprocating needle, of a work-clamp, means for producing relative jogging movements between said needle and work-clamp and means for periodically varying the length of said jogging movements, thereby to produce a series of buttonhole side-stitches and a series of barring stitches of greater length, and means for producing a series of piled up or relatively massed side-stitches and acting at points of change in the length of said jogging movements. 75

3. In a buttonhole sewing machine, the combination with a reciprocating and laterally jogging needle, needle-jogging means, and a work-clamp, of a cam adapted to impart longitudinal feeding movements to the work-clamp and having dwell portions for temporarily suspending such feeding movements intermediate the extreme positions of the work-clamp, actuating means for said cam including an adjustable element whereby the speed of movement of said cam may 100 be varied independently of the needle-jogging means, and means acting upon the needle-jogging means during the control of the clamp by said dwell portions of said cam for varying the amplitude of jogging 105 movements of the needle. 110
